Design No. 14,166, dated August 14, 1883.

UNITED STATES PATENT OFFICE.

JOSEPH FERGUSON, OF PHILADELPHIA, PENNSYLVANIA, ASSIGNOR TO
STEAD & MILLER, OF SAME PLACE.

DESIGN FOR A CHENILLE RUG.

SPECIFICATION forming part of Design No. 14,168, dated August 14, 1883.

Application filed July 3, 1883. Term of patent 3½ years.

To all whom it may concern:

Be it known that I, JOSEPH FERGUSON, a citizen of the United States, residing at Philadelphia, in the county of Philadelphia and State of Pennsylvania, have invented and produced a new and original Design for a Pattern to be Inwrought in Chenille and then into a Chenille Axminster or a Two-Face Smyrna Rug, in such colors or shades of materials as may be desired; and I do hereby declare that the photographic print accompanying this specification shows the one-half of a rug, and conveys to any one skilled in the art of weaving chenille fabrics and two-face Smyrna rugs a clear understanding of the same, and is sufficient to enable such persons to use my invention.

It is obvious that my newly-invented design may be inwrought in the rug single or two face. The single-face is known to the trade as "chenille Axminster" and the two-face as "reversible" or "Smyrna" rugs.

What I claim as my invention, and desire to secure by Letters Patent, is—

The design for a rug, as shown in the photographic print accompanying this specification.

JOSEPH FERGUSON.
